UNITED STATES PATENT OFFICE.

HERMANN O. NAUEN, OF NEW YORK, N. Y.

SEWING-MACHINE.

SPECIFICATION forming part of Letters Patent No. 240,449, dated April 19, 1881.

Application filed September 22, 1880. (No model.)

To all whom it may concern:

Be it known that I, HERMANN O. NAUEN, a citizen of the German Empire, residing at New York, in the county and State of New York, 5 have invented new and useful Improvements in Sewing-Machines, of which the following is a specification.

This invention relates to sewing-machines for manufacturing and other general purposes; 10 and it consists in certain novel combinations of parts, hereinafter fully described, and pointed out in the claims.

This invention is illustrated in the accompanying drawings, in which Figure 1 represents a plan or top view with the cloth-plate removed to expose the parts beneath it. Fig. 15 2 is a vertical cross-section on the line *xx*, Fig. 1. Fig. 3 is a similar section on the line *yy*, Fig. 1.

20 Similar letters indicate corresponding parts.

The letter A designates the machine-frame, and B a vibrating arm carrying an eye-pointed needle, *c*, which, together with a looping-hook, *d*, constitutes the stitch-forming mechanism.

25 The needle *c* is preferably curved concentrically to the axis of the vibrating arm B. The looping-hook *d* is fixed to a driving-shaft, E, on which is also fixed an eccentric for operating the feed-bar F in the usual manner, to this 30 feed-bar being applied the feed surface or dog *g*.

The vibrating arm B has its fulcrum on a rock-shaft, H, the arm being preferably formed in one piece therewith, and this shaft has its 35 bearings on pivots I I, which are fixtures of a laterally-projecting arm, A', on the machine-frame, while the shaft is connected with an eccentric fixed to the driving-shaft E by a rod, J, to receive the required motion.

40 Beneath the rock-shaft H is situated a shield, K, to keep the cloth out of contact therewith as it leaves the stitch-forming mechanism, and also to catch any drippings of oil, the rock-shaft being arranged with its fulcrum situated 45 substantially in a horizontal plane with the cloth-plate of the machine, (marked L,) and the cloth being allowed to pass under it or its bearings by a novel arrangement of the feed-bar and cloth-plate, hereinafter described.

50 In juxtaposition with the vibrating arm B

is located a second arm, N, which is hung on pivots o o, and carries the presser-foot P at its free end, the pivots o o applied to a bracket, Q, secured to the machine-frame and being adjustable. This presser-arm N is subjected to 55 the action of a spring, R, having a tendency to force and retain the same in a lower position, and a cam, S, is used for lifting and retaining the arm in an upper position, both the spring and cam being applied to a bracket, T, 60 secured to the machine-frame.

The usual location of the feed-bar F is in the rear of the stitch-forming mechanism, whereas in my machine the feed-bar is arranged at a point forward of the stitch-forming mechanism—namely, so that it extends in an opposite direction to the needle-arm B or presser-arm N from such mechanism—while the cloth-plate L terminates at a point forward of the laterally-projecting arm A', in which is mounted 70 the rock-shaft H, forming the fulcrum of the vibrating needle-arm B. In this manner a free space is left between the cloth-plate L and the fulcrum of the vibrating arm B, as well as beneath such fulcrum, for the escape of the 75 cloth.

For the purpose of lubricating the driving-shaft the machine-frame is provided with oil-wells U, and with each of these wells I combine a pad, V, of felt or other absorbent material.

I do not broadly claim a vibrating needle-arm arranged in a plane parallel to the motion of the feed dog or surface; neither do I broadly claim a presser-arm hinged at its rear end and 85 lifted by a cam and pressed to the feed-dog by a spring; but

What I claim as new, and desire to secure by Letters Patent, is—

1. The shaft E, provided with a looping-hook, *d*, in combination with a rod, J, connected with an eccentric fixed to the driving-shaft, the rock-shaft H, connected with the rod J, and the vibrating needle-arm B, arranged in a plane parallel to the motion of the feed-dog, all substantially as shown and described. 95

2. The combination, with the frame A, the feed mechanism, the rock-shaft H, and the vibrating arm B, attached to the shaft and arranged in a plane parallel to the motion of the 100

feed-surface, of the shield K, attached to the frame A and arranged beneath the rock-shaft, in rear of the feed mechanism, substantially as herein shown and described.

5 3. The combination, with the rock-shaft H, vibrating needle-arm B, the feed-bar, and the driving-shaft E, connected with both the rock-shaft and the feed-bar, of the presser-arm N, hinged at its rear end to the bracket Q, attached to the frame of the machine, the spring R, bearing on the upper edge of the presser-arm to press the same down, and the cam S,

arranged beneath the presser-arm to lift the same, the spring and cam being arranged in a bracket, I', all substantially as and for the purpose described. 15

In testimony whereof I have hereunto set my hand and seal in the presence of two subscribing witnesses.

HERMANN O. NAUEN. [L. S.]
